DESIGN FOR A POTTERY PIECE

Selma V. Murray, Kansas City, Mo.

Application May 28, 1945, Serial No. 119,777

Term of patent 7 years

(Cl. D29—28)

To all whom it may concern:

Be it known that I, Selma V. Murray, a citizen of the United States, residing at Kansas City, in the county of Jackson and State of Missouri, have invented a new, original, and ornamental Design for a Pottery Piece, of which the following is a specification, reference being had to the accompanying drawing, forming a part thereof.

Fig. 1 is a front elevational view of the pottery piece, showing my new design.

Fig. 2 is a side elevational view thereof.
Fig. 3 is a rear elevational view thereof; and
Fig. 4 is a top plan view thereof.

I claim:

The ornamental design for a pottery piece, as shown.

SELMA V. MURRAY.
